DESIGN FOR A HAWAIIAN GUITAR

Walter L. Fuller, Kalamazoo, Mich., assignor to Gibson, Inc., Kalamazoo, Mich., a corporation of Michigan

Application April 28, 1938, Serial No. 76,839

Term of patent 7 years

To all whom it may concern:

Be it known that I, Walter L. Fuller, a citizen of the United States, residing at the city and county of Kalamazoo and State of Michigan, have invented a new, original, and ornamental Design for a Hawaiian Guitar, of which the following is a specification, reference being had to the accompanying drawing, forming part thereof, in which:

Fig. 1 is a top perspective view,
Fig. 2 is a side elevation, and
Fig. 3 is an end elevation of a Hawaiian guitar, showing my new design.

I claim:
The ornamental design for a Hawaiian guitar,
as shown.

WALTER L. FULLER.
